DESIGN FOR A CHILD'S COMBINED FOOD
WARMER AND SERVICE PLATE

Richard E. Zipser, New York, N. Y.

Application June 11, 1946, Serial No. 130,611

Term of patent 3½ years

(Cl. D44—15)

To all whom it may concern:

Be it known that I, Richard E. Zipser, a citizen of the United States of America, residing at New York city, Borough of Manhattan, county and State of New York, have invented a new, original, and ornamental Design for Child's Combined Food Warmer and Service Plate, of which the following is a specification, reference being had to the accompanying drawing, forming part thereof.

In the drawing:

Fig. 1 is a perspective view of a child's combined food warmer and service plate showing my new design;

Fig. 2 is a perspective view thereof with the separable head and platter removed;

Fig. 3 is a side perspective view of the stopper;

Fig. 4 is a top perspective view of the separable platter.

I claim:

The ornamental design for a child's combined food warmer and service plate, substantially as shown.

RICHARD E. ZIPSER.
